SHOE

Abraham J. Weinstein, Brooklyn, N.Y., assignor of one-third to Robert Henderson, Short Hills, N.J.

Application July 26, 1957, Serial No. 674,350

1 Claim. (Cl. 36—45)

This invention relates to an improved article of foot-wear and the manner in which it is made.

An important object of the invention is the provision of an improved shoe which utilizes considerably less material than prior shoes of comparable style thereby making the shoe lighter and, for that reason, more comfortable for the wearer and is less costly to make because of the reduced quantity of material therein.

Another important object is the provision of an improved shoe which may be easily and economically produced from prefabricated parts of such relative shapes, for a given size, as to give greater assurance that the finished shoe will be of a precise desired size.

Another important object is to provide an improved shoe wherein stitching is avoided around the edge of the outer sole thereby avoiding a weakness present in many prior shoes.

Another important object is the provision of an improved shoe wherein the vamps are joined in a finished manner under the arch, thereby enabling use of an outer sole which covers little more than the step-on or wear surface of the bottom of the shoe.

Another important object is the provision of an improved shoe in which portions of the vamps which are underneath the arch continue uninterruptedly as a covering for the front or inside face of the heel of the shoe and are anchored underneath the top lift of the heel.

The foregoing and other more or less obvious objects are accomplished by this invention as set forth in the following description and illustrated in the accompanying drawings.

In the drawings:

Figure 1 is an elevational view of the inner side of a finished, illustrative shoe according to this invention.

Figure 2 is a top view of said shoe.

Figure 3 is a bottom view of said shoe.

Figure 4 is a front elevational view of said shoe.

Figure 5 is a rear elevational view of said shoe.

Figure 6 is a bottom view of said shoe in an intermediate stage of its manufacture.

Figure 7 is a longitudinal sectional view, substantially in the line 7—7 of Figure 2.

Figure 8 is a transverse sectional view, substantially on the line 8—8 of Figure 1.

Figure 9 is a bottom view of a prefabricated arch supporting shank for the shoe.

The shoe illustrated in the drawings is only one of many different styles in which shoes may be produced and utilized within this invention and, particularly with respect to the shoe's upper, linings may be provided although such linings are not shown in the drawing.

Although the shoe's upper may comprise a smaller or greater number of pieces, it is disclosed as comprising a collar 10, an inner-side vamp 12, an outer-side vamp 14, an inner backstay or counter 16, an outer backstay 18 and a collar binding 20; all said parts preferably being of suitable thin leather or more or less equivalent material.

2

The shoe's sole portion, as illustrated, comprises a bottom insert 22, an outer sole 24 and, preferably, a cushioning inner sole 26 and a sock lining 28. The insert 22 is of thin leather or other suitable sheet material; the outer sole 24 is of sole leather or more or less equivalent sole material; the inner sole 26 is preferably of granular cork or other suitable cushioning material; and the sock lining is of thin leather or equivalent material. In the illustrated shoe, the back of the sole portion has an arch support 30 embedded therein between the bottom insert 22 and the inner sole 26; said arch support comprising a rigid steel shank 32 embedded in a layer of granular cork which is sandwiched and cemented between outer sheets 36 of cardboard or leather.

The shoe has a heel 38 which, in the present disclosure, may be considered as of suitably shaped wood, although it may be of metal, relatively rigid, molded plastic material or other suitable relatively rigid material. The heel is commonly provided with a lift 40 of sole leather or other suitable material.

In making the shoe, according to this invention, the stated parts of the upper are stitched together and the bottom insert 22 is inserted and stitched thereinto before any last is used.

More particularly, the collar binding 20 is suitably stitched in place around the upper edge of the collar 10, the lower margins of said collar are suitably stitched in overlapping relation to the upper margins of the vamps 12 and 14, the lower margins of said vamps are brought together and stitched together preferably by means of a flat seam 41 which, as illustrated, extends longitudinally of and underneath the arch or instep portion of the shoe; the back margins of the collar are stitched to and in position underneath the side margin of the outer backstay 18; the inner backstay 16 is stitched into place; and the upper ends of the backstays 16 and 18 are suitably trimmed and stitched in position over the back ends of the binding 20.

It should be understood that all the mentioned pieces comprising the shoe are prefabricated to the proper shapes and sizes for each given size of shoe so that the assembly of the upper, as just described, without the use of a last, results in an upper which, in the finished shoe, will be of the desired size and shape and will fit properly with respect to sole portions of the shoe.

The upper and sole portions of the shoe may be put together by sewing the bottom insert 22, or equivalent insert, within the described upper of the shoe after which the outer sole 24 is cemented into place. The mentioned sewing of the insert 22 is performed before any association of the parts of the shoe with a last.

It may be observed from Figures 1, 3 and 6 that the stitching toward the back ends of the upper margins of the vamps 12 and 14, terminates at points X, approximately at the front edge of the heel 38, and that the material of said vamps continues rearwardly to form a flap 42, which, at the stage of manufacture shown in Figure 6, is in the nature of a free flap. Thus, before the bottom insert 22 is put into place, the ball and toe area of the upper is open as at 44 (Figure 6) and the heel area of the upper also is open as at 46.

The insert 22 is placed within the upper, either through the latter's top opening or through one of open areas 44 or 46, such placing of the insert being easily accomplished in the absence of any last. The insert 22 is preformed to such an exact size that when edges about its ball and toe portions and about its heel portion are in abutting relationship to adjacent edges of upper portions of the shoe, the resultant foot pocket of the shoe will be the exact size desired. In such abutting relationship, the said edges of the ball and toe portions of the insert 22 are zig-zag stitched as at 48, to adjacent edges of the shoe's upper.

and the edges of the heel portion of the insert are zig-zag stitched as at 50 to adjacent edges of the shoe's upper. Before such placing of the insert 22, a suitable cement may be applied to the portion of the bottom surface of insert 22 which immediately overlies adjoined portions of the vamps 12 and 14 to cause adhesion of said insert thereto.

After the described placing and securing of insert 22, the arch support 30 is cemented into place upon the back end of the insert 22, the heel 38 is cemented into place and firmly secured by screws 52 extending through suitable screw holes in the arch support 30; said screws also operating to firmly secure the arch support 30 in place.

At this stage of operations, an expansion last is inserted into the partly finished shoe whereafter the outer sole 24 is cemented into place. Also, the flap 42 is cemented to the front or inner surface of the heel and the end of said flap is held firmly underneath the lift 40 which, at that stage, is nailed or otherwise suitably secured upon the bottom of the heel.

After adequate setting of the cement in the thus-far formed shoe, the latter is taken off the last, whereafter the inner sole 26 and then the socklining 28 are suitably cemented into place.

It may be seen from Figure 8 that the described abutting of the ball and toe portions of the insert 22 with adjacent portions of the upper of the shoe provide uniformity of thickness of the material between the outer sole 24 and the inner sole 26 so that the latter will remain substantially flat or undeformed, thereby providing greater comfort for the wearer. A similar abutting relationship of the back or heel end of said insert with adjacent parts of the upper of the shoe enables the arch support 30 and the heel 38 to be more perfectly fitted and secured in place.

It is important to note that because of the fact that the vamps 12 and 14 are extended and seamed together as at 41 to give a finished appearance underneath the arch or instep of the shoe, the outer sole 24 need not extend thereunder but need only be large enough to provide a sole at the "step on" area of the front of the shoe. This not only economizes in sole leather but also gives the shoe some added flexibility within the limits permitted by the arch support 30 and some reduction of the tightness of fit about the instep of the wearer's foot. It should be observed also that the zig-zag stitching 48 and 50 is substantially inward of the edges of the outersole 24 and of

the heel 38 so that the stitches are well protected against possible rupture and also, by being invisible, improve the appearance of the shoe.

Although the flat seam 41, as illustrated, is centrally located, that seam, nevertheless, may be located somewhat off-center toward one or the other side of the bottom of the shoe.

Although the invention has been illustrated and described with reference to a ladies shoe having a heel of substantial height, this invention is also applicable to men's shoes or other shoes having relatively low heels. The principal consideration with respect to heels is that the latter should be of sufficient height that the adjoining portions of the upper, underlying the arch, should be raised from the floor or i.e. should not constitute a "step on" area of the shoe.

It will be understood that the present concepts may be utilized in various ways other than herein specifically shown and described without, however, departing from the invention as set forth in the following claim.

What I claim is:

A shoe having an upper, a heel, and an outer sole substantially spaced from the heel, a part of the upper extending completely across the underside of the shoe and completely occupying the space between the said heel and sole, the shoe further including a bottom insert having toe, ball, and heel portions and an intermediate portion between said ball and heel portions and overlying the mentioned part of the upper, marginal portions toward opposite ends of said insert being stitched in abutting relation to adjacent marginal portions of the upper of the shoe, and substantial, opposite marginal parts of said intermediate portion of said insert being free of stitching with respect to the upper of the shoe.
